AUTOMOBILE GRILLE

Alfred E. Niksa, Royal Oak, Mich., and René C. Pinchuk,
San Francisco, Calif., assignors to Chrysler Corporation, Highland Park, Mich., a corporation of Delaware

Filed June 27, 1960, Ser. No. 61,127

Term of patent 7 years

(Cl. D14—18)

Fig. 1 is a front view of an automobile grille embodying our new design;

Fig. 2 is a top plan view thereof;

Fig. 3 is an end elevational view thereof; and

Figs. 4, 5, 6 and 7 are sectional views taken on the lines 4—4, 5—5, 6—6 and 7—7, respectively, of Fig. 1.

We claim:

The ornamental design for an automobile grille, substantially as shown.
